Primary Examiner — Anhdao Doan(74) *Attorney, Agent, or Firm* — Studebaker & Brackett PC(57) **CLAIM**

The ornamental design for a brain thermal tunnel headgear, as shown and described.

DESCRIPTION

FIG. 1 is a front perspective view showing my new design for a brain thermal tunnel headgear,

FIG. 2 is a front view thereof,

FIG. 3 is a rear view thereof,

FIG. 4 is a top view thereof,

FIG. 5 is a bottom view thereof,

FIG. 6 is a left side view thereof, and,

FIG. 7 is a right side view thereof.

The broken lines in FIG. 1 represent an environment and form no part of the claimed design.
